WASHBOARD

Maude L. E. Irwin, Hayward, Calif.

Application August 19, 1957, Serial No. 47,435

Term of patent 14 years

(Cl. D49—1)

Fig. 1 is a front elevational view of a washboard showing my new design; and

Fig. 2 is a side sectional elevational view thereof, this view being taken on the line 2—2 of Fig. 1.

I claim:

The ornamental design for a washboard, as shown.
